UNITED STATES PATENT OFFICE

108,947

DESIGN FOR AN ELECTRIC MIXER

Robert Heller, New York, N. Y., assignor to The
A. C. Gilbert Company, New Haven, Conn., a corporation of Maryland

Application January 12, 1938, Serial No. 74,216

Term of patent 14 years

To all whom it may concern:

Be it known that I, Robert Heller, a citizen of the United States, residing in New York, in the county of New York and State of New York, have invented a new, original, and ornamental Design for an Electric Mixer, of which the following is a specification, reference being had to the accompanying drawings, forming part thereof, in which

Fig. 1 is a side elevational view of an electric mixer showing my new design;

Fig. 2 is a front end elevation on a larger scale; and

Fig. 3 is a section on line 3—3 of Fig. 2.

I claim:

The ornamental design for an electric mixer substantially as shown.

ROBERT HELLER.
